Primary Examiner — Christian P. McLean*Assistant Examiner* — Jessica Lynn Devilbiss(74) *Attorney, Agent, or Firm* — BEKIARES ELIEZER LLP(57) **CLAIM**

The ornamental design for a trailer alignment tool set, as shown and described.

DESCRIPTION

FIG. 1 is a perspective view of a trailer alignment tool set showing my new design;

FIG. 2 is a first side view thereof;

FIG. 3 is a second side view thereof;

FIG. 4 is a top view thereof;

FIG. 5 is a bottom view thereof;

FIG. 6 is a back view thereof;

FIG. 7 is a front view thereof; and,

FIG. 8 is a reduced size perspective view of the trailer alignment tool set.

The broken lines illustrate portions of the trailer alignment tool set that do not form a part of the claimed design. Shading lines are included in the drawings. The cutaway symbols illustrated in break lines in the drawings indicate a symbolic break in the length of the design for the trailer alignment tool set indicating an indeterminate length. The appearance of any portion of the article between the break lines forms no part of the claimed design.
